UNITED STATES PATENT OFFICE.

FREDERICK A. WISWELL, OF BEEBE PLAIN, ASSIGNOR TO CHARLES C. COLBY, OF STANSTEAD, QUEBEC, CANADA.

MACHINE FOR MAKING WIRE ROPE.

SPECIFICATION forming part of Letters Patent No. 276,318, dated April 24, 1883.

Application filed August 12, 1882. (No model.)

To all whom it may concern:

Be it known that I, FREDERICK A. WISWELL, a citizen of Canada, residing at Beebe Plain, in the county of Stanstead and Province of Quebec, Canada, have invented certain new and useful Improvements in Machines for Making Wire Rope; and I do hereby declare the following to be a full, clear, and exact description of the invention, such as will enable others skilled in the art to which it appertains to make and use the same.

This invention relates to machines for the manufacture of wire rope, and has for its objects, first, to effect the manufacture of a rope in which the strain applied thereto will be borne by all the wires composing the same; and, secondly, to obtain a cheaper and superior working rope.

The machine comprising my invention is capable of laying individual wires around cores to form strand-cores; next, laying individual wires around the strand-cores to form strands, and, lastly, laying the strands around a main or rope core to form the rope, all in one continuous operation.

For a full understanding of my invention reference is made to the annexed drawings, and to the following description and claims.

Referring to the drawings, Figure 1, Sheet 3, is a plan view of my improved machine, some of the parts being broken away and others removed to more clearly illustrate the principal working portion of the machine. Fig. 2, Sheet 2, is a front elevation of one of the general heads or groups of mechanism with a number of the spool-carriers removed and the arm *g* broken away. Fig. 3 is a longitudinal vertical section thereof. Fig. 4 is an end view of one of the spool-carriers. Fig. 5 is a similar view, illustrating the end opposite to that shown in Fig. 4. Fig. 6 is a front elevation, partly in section, of a spool-carrier. Fig. 7, Sheet 3, is an enlarged sectional view of the strand-laying-head mechanism. Fig. 8 is an elevation of the slotted sector for supporting the adjustable gear between the driving and main shafts, and Fig. 9 is a transverse section of a hoisting-rope.

Corresponding parts in the several figures are indicated by similar characters of reference.

In the accompanying drawings, A marks a frame adapted to support the operating mechanism, and B the central hollow shaft, supported at its rear end in bearings *a a'*, secured to the frame A, and at its forward end in the rope-laying head C, which is held in bearings *a'* in the said frame A. This rope-laying head C may be of any known form or construction suitable for the purpose, though I have shown that form which is fully described in an application filed by me July 11, 1882, numbered 66,359, to which reference is made.

Two hubs, D G, are secured to the main shaft B at a suitable distance apart, and are respectively provided with six radiating arms, *d g*, whose extremities support six general heads or groups of mechanism, which are designed to manufacture the strand-cores and strands, and since said heads are alike in construction and operation I confine myself to a specific description of one of them, as illustrated in Figs. 2 and 3 of the drawings. Referring, then, to said figures, *d* marks one of the arms of the hub D, partly broken away, and having the sleeve *d'* secured to its end, said sleeve receiving and supporting the hollow shaft *e*. Secured with a set-screw, *e'*, to the hollow shaft *e*, in front of the sleeve *d'*, is the head E, provided with a number of arms, *e'*, projecting from its rim, said arms designed to receive the spool-carriers, to be presently described. Secured to the head E, opposite each other, are two arms, F F', which project forward and inward, and at the extremity of the shorter arm, F', form an annular bearing, *f*, (shown in Fig. 1.) for the strand-core-laying head, which will be presently set forth. The other arm, F, extends forward of the strand-core-laying head, and ends in the hub *f*, which has a rim, *f'*, connected to said hub by means of the spokes *f*. (Shown in Fig. 2.) The said arm F, hub *f*, rim *f'*, and spokes *f* are formed in the present instance in one piece. The rim *f'* has a bearing in the end of the arm *g*, as shown. The base H of the strand-laying head is screwed into the hub *f*, and is curved and tapered, as shown, to receive the sleeve *h*, which has its inner surface curved in such manner as to fit the curved surface of the base, as more fully indicated in Fig. 7. The sleeve *h* is held on the base H by means of the

tube I, which passes through base H, and receives at its forward end the spider J, which in turn bears against the sleeve h. The tube I receives a thumb-nut, i, at its rear end, which 5 presses against a coiled spring, i', encircling said tube between said thumb-nut and the end of the base H, as clearly shown in Fig. 7. A set-screw, h', passes partly through the base H and into a slot, i'', in the tube I, to prevent 10 a rotation of the tube while permitting longitudinal motion thereof. By means of the thumb-nut i and coiled spring i', the sleeve h can be properly adjusted on its base, yet not so rigidly but that there will be sufficient 15 play or yielding of parts to permit wire having irregular surfaces to pass between the sleeve and its base to prevent breakage of wires. As shown in Fig. 2, the spider J has a number of slots, j, in its periphery, to contain each an individual wire, whereby entanglement of the wires with one another will be prevented and their proper laying into the strand facilitated. I provide the concaved surface in the base H, and the contiguous convexed surface in the 25 sleeve h, to cause said base and sleeve and the spider J to act as a wire-straightener.

It will be seen by referring to Fig. 7, which shows sleeve h removed from close contact with base H, to permit the passage of a wire between them, that said wire bears against the parts at three points—namely, against base H at its largest diameter, against the central part of the curved surface of the sleeve h, and against the spider J in one of its slots. Further, it will 30 be observed that the portion of the curved surface of sleeve h against which the wire bears is at a point below a right line drawn from the bearing-points of the base and spider. This construction is provided so that upon drawing 35 the wire through the parts it will be bent to a curve which shall approximate the curve otherwise given to a wire when laid into a strand. By this operation of parts all bends or curves that may be in the wire as it leaves a spool 40 will be removed and the curvature or bend given to it by the described mechanism will only remain. Further, by reason of this operation of parts and the fact that said parts are adjustable, a complete and thorough tension mechanism 45 is provided, which is capable of imparting an unvarying tension on all the individual wires passing between said parts, the said tensile strain being applied near the point of lay. By this construction the parts act in a three-fold capacity, thus dispensing with independent tension and straightening mechanism and 50 greatly simplifying the construction of the machine.

k marks a hollow shaft partly inclosed by 55 the shaft e, but extending at both ends beyond it, and having the disk K secured to it in front of the head E with a set-screw, k'. This disk is provided with a number of arms, k², projecting from its face, to economize space, instead 60 of from its periphery, as in the case of the head E, said arms k² designed to bear spool-carriers containing wire-bearing spools.

Formed in one piece with the hub of the disk K, and extending forward therefrom in a curved manner, as shown, is an arm, L, which ends in the hub l and rim l', formed in one piece therewith, said parts supporting the strand-core-laying head composed of the curved base M, sleeve m, spider N, slotted tube m', set-screw m², thumb-nut n, and coiled spring n', all of which 70 are constructed in a manner similar to the parts composing the strand-laying head, with the single exception that the spider N has a less number of slots than the spider J, because of the less number of wires used in the construction 75 of the strand-core. The strand - core - laying head has all the capabilities incident to the strand-laying head, as described hereinbefore.

Referring to one of the spool-carriers (illustrated in Figs. 4, 5, and 6) that are secured to the arms e² of the strand-head E, and the arms k² of the disk K, O marks the base, o the rigid arm disposed at right angles to said base, and o' the swinging arm pivoted to the opposite end thereof. Engaging with the pair 80 of lugs o², formed one on each side of the rigid arm o, is a friction-block, P, held in frictional contact with the friction-wheel Q, journaled in the upper end of arm o, by means of the spring p, abutting against the adjusting-screw p', 85 working in the lower part of said arm o. Cast on the inner face of the friction-wheel is a corrugated or ribbed stud, q, which partly projects into the hub of the spool R, and, by reason of the corrugations or ribs, causes the 90 spool and friction-wheel to be revolved together when the spool is rotated. The swinging arm is provided at its end with a smooth or, if desired, corrugated stud, q', working on the pin q², and partially inserted in the contiguous end of the hub of the spool R, and is 95 held in such position to retain said spool in the spool-carrier by means of the bent retaining-wire o³, which is passed around the swinging arm o', engages with the cam-web o⁴ on 100 said arm, and has its ends secured to the arm o, as clearly shown in Fig. 6. By this construction of parts it will be seen that the spool R can be readily removed from the spool-carrier by pressing or forcing the retaining-wire o³ 105 away from the cam-web o⁴ and toward the base O, to permit arm o' to be swung outward to release the spool, and, further, that the friction between wheel Q and block P can be increased or diminished by means of 110 the adjusting-screw p'. This frictional mechanism is designed to prevent the spool revolving by reason of the "spring" of the wire coiled thereon. The base O is provided with a projection having a circular opening, o⁵, and 115 set-screw o⁶, to enable the spool-carrier to be placed and retained on an arm, e² or k², of the head E or disk K. It will be noticed from the drawings that the head E is capable of carrying twelve spool-carriers containing each a 120 wire-bearing spool, R, and that the disk K is adapted to carry six spool-carriers, which also 125 contain wire-bearing spools.

S marks a core-spool suitably held on an

arm, s , screwed into the sleeve d' , to which also is held the shield s' , having retaining-studs s^2 , said shield extending in an outward and then inward curved direction to the rear end of shaft k , by which means a core for the strand-core may be passed from the core-spool S to and into the hollow shaft k , and thence to and into the tube m' of the strand-core-laying head to become incorporated into the strand-
core at the spider N .

The spaces between the spokes f^2 , rim f' , and base f permit wires from the spools on the head E to be passed to the strand-laying head, and the same provision is made with reference to the wires passing from the spools on the disk K to the strand-core-laying head.

As shown in Fig. 3, the shaft e is provided in rear of the sleeve d' with a bevel-gear, e^3 , and the shaft k has a similar gear, k^3 , at its rear end, both of which mesh with the bevel-gear t on the outer end of shaft T , held in bearings t' , secured to the back of the arm d .

As shown in Fig. 1, the inner end of shaft T has a bevel-gear, t^2 , engaging with the bevel-gear u , cast in one piece with or secured to the spur-gear U to form a double gear, which is free to turn on the main shaft B .

Mesning with the spur-gear U of the double gear-wheel is an idle-wheel, V , adjustably held by means of a journal bolt, v , in the slotted sector v' , secured to the frame A . The idle-gear V engages in turn with the pinion w on the shaft W , held in bearings to the frame A . Larger or smaller pinions may be placed on the shaft W in lieu of the pinion w . The slot v^2 in the sector v' is concentric with the periphery of the main shaft B , so that when a larger or smaller pinion is placed on the shaft W the idle-gear V may be adjusted in the slotted standard to cause it to mesh with the spur-gear U and the pinion w , whereby an increased or diminished speed will be transmitted from shaft W to said double gear-wheel, from which motion is communicated to the strand-head E through shaft T , its gears t t^2 , bevel-gear e^3 , and shaft e , and to disk K through said shaft T , its gears, the bevel-gear k^3 , and shaft k .

Keyed to the shaft W is a spur-gear, w' , meshing with the idle-gear x , held by a journal-bolt, x' , to the arm x^2 , forming part of the sleeve X , which is free to turn on main shaft B . The arm x^2 is removably held to the standard x^3 to insure the proper meshing of idle-gear x with gear w' and spur-gear X' , keyed to the main shaft B .

w^2 marks a band-wheel keyed to shaft W , through which motion may be imparted to said shaft from a suitable motor.

Y marks a reel held in bearings to the frame A below the main shaft, from which a suitable rope-core may be passed to and through the main shaft B to the rope-laying head C .

y indicates a shield to guide the rope-core to the shaft B , and y' a pivoted lever which rests on one of the disks of the reel, and is provided with a weight, y^2 , whereby the rope-

core will be drawn from the reel under tension to prevent a too rapid unwinding thereof.

With the exception of the slotted sector v' , with its gear V , and the fact that one idle-gear instead of two is interposed between gear w' on shaft W and gear X' on main shaft B , the foregoing-described drive and reel mechanism, including shafts T , are identical with those described in the application hereinbefore mentioned, to which reference is made for a more specific description.

The drawing-off mechanism shown in Fig. 1 is also identical with that shown and described in the application above referred to, and, without entering into a detailed description thereof, it is sufficient to say that as the rope leaves the rope-laying head C it is passed one or more times around the rotating drawing-off wheel Z , is prevented fromlapping on itself by means of the inverted cones z , and is taken from the drawing-wheel Z , as it is drawn thereon, by the oppositely-revolving rolls z' , whence it may be passed to a suitable reeling device, to which motion may be given through a belt engaging with the pulley z^2 .

It will be seen from the foregoing that the main shaft B receives motion through gear X' , keyed thereto, while the groups of mechanism which are designed to form the strands and strand-cores receive motion from the double gear-wheel u U , loose on said main shaft B .

As now constructed and described, my improved machine is capable of making a rope for hoisting purposes—generally termed “hoisting-rope”—said rope being composed of six wires laid around a wire center or core to form a strand-core, twelve wires laid around a strand-core to form a strand, and six strands laid around a main or rope core to form the rope shown in Fig. 9.

Assuming that the six groups of mechanism contain the required number of spools R , filled with wire, the core-spools S are filled with the required cores, the reel Y contains the proper rope-core, the machine is properly “threaded,” and the wires are drawn forward around the drawing-wheel Z , and through the drawing-rolls z' , the operation of the parts to make the rope shown in Fig. 9 will be as follows: Upon giving motion to the described drive mechanism, the disks K are rotated on their axes, the individual wires are drawn from the spools R in the spool-carriers on said disks, and, passing between the base M and sleeve m of the strand-core-laying heads, are bent, subjected to tensile strain, and laid around the core-wires, passing from the core-spools S to and into the shafts k and tubes m' to the spiders N , to form the strand-cores, which pass to and through the tubes I to the spiders J of the strand-laying heads. During this operation of parts the heads E revolve in an opposite direction to that of the disks K , the individual wires are drawn from the spools R in the spool-carriers on said heads, and, passing between the sleeve h and base H of the strand-laying heads, are

bent, subjected to tensile strain, and laid around the strand-cores to form strands, which, six in number, pass over the grooved rollers g' , having bearings in the brackets g'' , secured to the arms g , to and into the rope-laying head C , and are laid—in a reverse direction to the lay of the wires around the strand-cores—around the rope-core, passing from the reel Y to and into the hollow main shaft B , to said rope-laying head C , to form the rope, said rope thence passing around the wheel Z and through the drawing-rolls z' to a suitable reeling device.

If desired, the disks K may be caused to revolve in the same direction as that of the heads E by removing the shields s' from the sleeves d' , to permit the bevel-gears k^3 to be removed from the shafts k , then tightening the set-screws c^4 , to cause the shafts e and k to move together, and replacing the shields s' .

It will be observed that the strand-core-laying heads rotate with the disks K , while the strand-laying heads rotate with the heads E ; further, that the groups of mechanism are carried around the axis of the main shaft B by means of the radiating arms d, g .

When the heads E and disks K are filled with spool-carriers containing wire-bearing spools, the hoisting-rope shown in Fig. 9 will be manufactured upon putting the machine in motion.

By the adjustability of many parts of the machine, as described hereinbefore, a variety of ropes may be made on my machine differing from that shown in Fig. 9 in the arrangement and number of wires.

The process or method described herein forms the subject-matter of an application filed by me on the 15th day of December, 1882, numbered 79,321, and no claim thereto is herein set up.

Having thus described my invention, what I claim is—

1. A series of rotating heads provided with arms adapted to carry wire-bearing spools, and having each a laying-head connected to and rotating with said heads, a series of rotating disks provided with arms adapted to carry wire-bearing spools, and having each a laying-head connected to and rotating with said disks, and a revolving main shaft provided with a rope-laying head, in combination, substantially as set forth.

2. A series of rotating heads provided with arms adapted to carry wire-bearing spools, and having each a laying-head connected to and rotating with said heads, and adapted to remove bends in the wires and impart a bend of its own thereto, a series of rotating disks provided with arms adapted to carry wire-bearing spools, and having each a laying-head connected to and rotating with said disks, and adapted to remove bends in the wires and impart thereto a bend of its own, and a revolving main shaft provided with a rope-laying head, in combination, substantially as set forth.

3. A series of rotating heads provided with arms adapted to carry wire-bearing spools, and having each a laying-head connected to and rotating with said heads, and adapted to subject the wires passing therethrough to tensile strain, a series of rotating disks provided with arms adapted to carry wire-bearing spools, and having each a laying-head connected to and rotating with said disks, and adapted to subject the wires to tensile strain, and a revolving main shaft provided with a rope-laying head, in combination, substantially as set forth.

4. A rotating hollow shaft, e , having a head provided with arms secured thereto, a number of spool-carriers adapted to be attached to said arms and to contain wire-bearing spools, a laying-head connected to and rotating with said head, a rotating shaft having its bearings in the hollow shaft e , and provided at its forward end with a disk having arms, a number of spool-carriers adapted to be attached to said arms and to contain wire-bearing spools, and a laying-head connected to and rotating with said disk, in combination, substantially as and for the purpose set forth.

5. A sleeve, d' , having an arm, s , adapted to carry a core-bearing spool, a rotating hollow shaft, e , having its bearings in the sleeve d' , and provided with a head having arms, a number of spool-carriers adapted to be attached to said arms and to contain wire-bearing spools, a laying-head connected to and rotating with said head, a rotating hollow shaft, k , having its bearings in the hollow shaft e , and provided at its forward end with a disk having arms, a number of spool-carriers adapted to be attached to said arms and to contain wire-bearing spools, and a laying-head connected to and rotating with said disk, in combination, substantially as and for the purpose set forth.

6. The rotating hollow shaft e , head E , secured to said shaft, and provided with arms e^2 , adapted to carry wire-bearing spools, a laying-head connected to head E , the rotating shaft k , having its bearing in the hollow shaft e , and provided with disk K , having a number of arms adapted to carry wire-bearing spools, and a laying-head connected to disk K , in combination, substantially as set forth.

7. A spool-carrier consisting of a base having a rigid arm, a swinging arm, and means for holding the swinging arm parallel with the rigid arm to retain a spool between said arms, and provided with a friction-wheel having a corrugated stud adapted to engage with the spool, and a friction-block, substantially as set forth.

8. A spool-carrier consisting of a base having a rigid arm, a swinging arm, and means for holding the swinging arm parallel with the rigid arm to retain a spool between said arms, and provided with a friction-wheel having a corrugated stud adapted to engage with the spool, a friction-block, and means for regulating the pressure between said block and wheel, substantially as set forth.

9. A spool-carrier having a fixed arm, the swinging arm o' , provided with a cam-web, and the bent retaining - wire, substantially as set forth.
- 5 10. The improved spool - carrier consisting of the base O , having rigid arm o , friction-wheel Q , its stud q , block P , its spring p , adjusting-screw p' , swinging arm o' , its cam-web, pin, and stud, and the retaining-wire, substantially as shown and described.
- 10 11. The base H , having sleeve h and set-screw h' , the slotted tube I , provided with a thumb-nut, and the spider secured to the forward end of said tube, in combination, substantially as set forth.
- 15
12. The combination, with the base H , having the sleeve h and set-screw h' , of the slotted tube I , provided with a thumb - nut, and means secured to the forward end of the tube for retaining the sleeve on its base, substantially as and for the purpose set forth.

In testimony whereof I affix my signature in presence of two witnesses.

FREDERICK A. WISWELL.
